(57) **CLAIM**

The ornamental design for a modular workstation, as shown and described.

DESCRIPTION

FIG. 1 is a front view of a modular workstation including a chair, according to the present invention.

FIG. 2 is a back view of the modular workstation of FIG. 1.

FIG. 3 is a left side view of the modular workstation of FIG. 1.

FIG. 4 is a right side view of the modular workstation of FIG. 1.

FIG. 5 is a top view of the modular workstation of FIG. 1.

FIG. 6 is a bottom view of the modular workstation of FIG. 1.

FIG. 7 is a perspective view of the modular workstation of FIG. 1.

FIG. 8 is a front view of a modular workstation in an alternate position of use, with the chair shown in a stowed configuration.

FIG. 9 is a back view of the modular workstation in the alternate position of use of FIG. 8.

FIG. 10 is a left side view of the modular workstation in the alternate position of use of FIG. 8.

FIG. 11 is a right side view of the modular workstation in the alternate position of use of FIG. 8.

FIG. 12 is a top view of the modular workstation in the alternate position of use of FIG. 8.

FIG. 13 is a bottom view of the modular workstation in the alternate position of use of FIG. 8; and,

FIG. 14 is a front perspective view of the modular workstation in the alternate position of use of FIG. 8.

The broken lines included in FIGS. 1-14 are for the purpose of illustrating environmental structure and portions of the modular workstation that form no part of the claimed design. In FIGS. 1-14, the modular workstation is shown positioned at the wall, with the wall being shown in the environment. The wall forms no part of the claimed design.

In FIGS. 3-7 and 10-14, the break lines and brackets represent a symbolic break in depth of the claim, and the appearance of any portion of the modular workstation

(Continued)

between the break lines and brackets forms no part of the claimed design. The break lines and brackets form no part of the claimed design.

1 Claim, 14 Drawing Sheets
